(57) **CLAIM**

The ornamental design for a slideable closure for containers, as shown and described.

DESCRIPTION

FIG. 1 is a top perspective view of a slideable closure for containers showing my new design;

FIG. 2 is a bottom plan view thereof;

FIG. 3 is a right side elevation view thereof;

FIG. 4 is a left side elevation view thereof;

FIG. 5 is a top plan view thereof;

FIG. 6 is a front elevation view thereof;

FIG. 7 is a rear elevation view thereof;

FIG. 8 is a top perspective view of a second embodiment, showing my new design;

FIG. 9 is a bottom plan view thereof;

FIG. 10 is a right side elevation view thereof;

FIG. 11 is a left side elevation view thereof;

FIG. 12 is a top plan view thereof;

FIG. 13 is a front elevation view thereof; and

FIG. 14 is a rear elevation view thereof;

FIG. 15 is a top perspective view of a third embodiment, showing my new design;

FIG. 16 is a bottom plan view thereof;

FIG. 17 is a right side elevation view thereof;

FIG. 18 is a left side elevation view thereof;

FIG. 19 is a top plan view thereof;

FIG. 20 is a front elevation view thereof; and

FIG. 21 is a rear elevation view thereof;

FIG. 22 is a top perspective view of a fourth embodiment, showing my new design;

FIG. 23 is a bottom plan view thereof;

FIG. 24 is a right side elevation view thereof;

FIG. 25 is a left side elevation view thereof;

FIG. 26 is a top plan view thereof;

FIG. 27 is a front elevation view thereof; and,

FIG. 28 is a rear elevation view thereof.
